The ornamental design for an RFID unit reader, as shown and described.

DESCRIPTION

FIG. 1 is a front view showing our new design for an RFID unit reader;

FIG. 2 is a rear view of the RFID unit reader of FIG. 1;

FIG. 3 is a top plan view of the RFID unit reader of FIG. 1;

FIG. 4 is a bottom plan view of the RFID unit reader of FIG. 1;

FIG. 5 is a left side view of the RFID unit reader of FIG. 1;

FIG. 6 is a right side view of the RFID unit reader of FIG. 1; and,

FIG. 7 is a perspective view of the RFID unit reader of FIG. 1.
